UNITED STATES PATENT OFFICE.

LOUIS V. ARONSON, OF NEWARK, NEW JERSEY, ASSIGNOR TO THE ART METAL WORKS, OF NEWARK, NEW JERSEY.

DESIGN FOR A CLOCK-CASE.

SPECIFICATION forming part of Design No. 36,084, dated September 30, 1902.

Application filed April 26, 1902. Serial No. 104,883. Term of patent 3½ years.

To all whom it may concern:

Be it known that I, LOUIS V. ARONSON, a citizen of the United States, residing at Newark, in the county of Essex and State of New Jersey, have invented and produced a new, original, and ornamental Design for a Clock-Case, of which the following is a specification, reference being had to the accompanying drawings, forming a part thereof.

10 Figure 1 is a front elevation of a clock-case embodying my design. Fig. 2 is a side elevation of the same.

As shown in the accompanying drawings, the leading or material feature of my design is 15 the female figure supporting the clock-socket.

This design comprises a female figure loosely draped in a gown laced at the bust and belted in at the waist, with a sash passed around her body, tied in a loose knot, and always reaching to the end of the loosely-flowing gown, the graceful folds of which surround

the figure and form the base. The arms of the female figure are in an uplifted position supporting the clock-socket.

In the illustrations, *a* represents the female figure, as shown; *b*, the sash; *c*, the folds of the gown. *d* represents the base, and *e* the arms of the figure.

The whole design is in the French style and known as the "Art Neu-Veau." 25 30

Having thus described my invention, what I claim is—

The ornamental design for a clock-case as herein shown and described.

Signed at Newark, in the county of Essex 35 and State of New Jersey, this 24th day of April, 1902.

LOUIS V. ARONSON.
